SHIP

James E. Sykes, Seattle, Wash.

Application June 12, 1943, Serial No. 490,649

2 Claims. (Cl. 114—66.5)

The present invention relates to new and useful improvements in ships and has for its primary object to provide, in a manner as hereinafter set forth, a sea going combination cargo and passenger vessel of the character described which, when underway, is adapted to plane on the water at great speed.

Another very important object of the invention is to provide an ocean going vessel of the aforementioned character which embodies novel propulsion means.

Still another very important object of the invention is to provide an ocean going ship of the hydroplane type wherein the entire hull of the vessel is completely closed.

Other objects of the invention are to provide a ship of the character set forth which will be comparatively simple in construction, strong, durable, sea worthy, and which may be constructed and operated at low cost.

All of the foregoing and still further objects and advantages of the invention will become apparent from a study of the following specification, taken in connection with the accompanying drawings wherein like characters of reference designate corresponding parts throughout the several views, and wherein:

Figure 1 is a view in side elevation of a ship constructed in accordance with the present invention.

Figure 2 is a top plan view thereof.

Figure 3 is a view in vertical longitudinal section through the vessel, taken substantially on the line 3—3 of Figure 2.

Figure 4 is a view in front elevation.

Figure 5 is a rear elevational view.

Figure 6 is a bottom plan view.

Figures 7, 8, 9 and 10 are cross-sectional views, taken substantially on the lines 7—7, 8—8, 9—9 and 10—10, respectively, of Figure 3.

Figure 11 is a fragmentary view, partly in side elevation and partly in section, showing means for turning the airplane and holding it in any position to which it is turned.

Referring now to the drawings in detail, it will be seen that the embodiment of the invention which has been illustrated comprises a closed, stream-lined hull of suitable dimensions which is designated generally by reference numeral 1. The hull 1 includes spaced inner and outer walls 2 and 3, respectively. Braces 4 are provided between the inner and outer walls 2 and 3 of the hull 1.

Fore and aft control cabins 5 and 6, respectively, are provided on the bow and stern of the

hull 1. Mounted at suitable locations on the hull 1 are gun turrets 7. Also mounted on the hull 1 is a plurality of search lights 8. Catwalks 9 are provided on the sides of the hull 1. Hatches 10 provide access to the hull 1.

Extending longitudinally in the hull 1 is a vertical partition 11. Built into the partition 11 is an air supply and discharge conduit 12 from which air may be taken and forced to the various parts of the ship and to which the spent air may be delivered for discharge at the rear end of the ship, which conduit extends from end to end of the hull 1. Transverse bulkheads 13 at longitudinally spaced points provide chambers or compartments 14 in the hull 1.

As illustrated to advantage in Figure 7 of the drawings, tracks 15 in the front of 1 beams are mounted transversely in the hull 1 adjacent certain of the hatches 10. Booms 16 are suspended from the tracks 15 and operable thereon through the medium of carriages 17. The booms 16 are adapted to be projected laterally through the adjacent hatches to facilitate placing in position suitable gang planks 19 for loading or unloading the vessel. Suitable tackle 20 is provided for supporting the booms 16 in extended position. Any desired means, as at 21, may be provided for operating the booms 16.

As best seen in Figure 3 of the drawings, hull 1 further includes a suitable number and arrangement of decks 22. Twin rudders 23 are mounted beneath the stern of the vessel. Also mounted beneath the stern portion of the vessel are triple screw propellers 24. Diesel engines 25 in certain of the compartments 14 drive the propellers 24.

Mounted longitudinally beneath the aft portion of the hull 1 and extending at a forward inclination relative to the bottom thereof is a hydrofoil 26. Plates 27 rigidly support the surface 28 of the hydrofoil 26. Mounted longitudinally beneath the surface 28 of the hydrofoil 26 are three spaced, parallel keels 29. As seen in Figure 6 of the drawings, the outer keels 29 are comparatively long. Longitudinal T irons 30 beneath the surface 28 further strengthen the hydrofoil 26.

Mounted on the forward portion of the hull 1, rearwardly of the cabin 5, is a turntable 31. A multi-motored airplane 32 is fixed on the turntable 31. It will be observed that the airplane 32 comprises a plurality of tractor and pusher propellers. Any suitable means may be provided to turn the airplane 32 and to hold it in any position to which it is turned. A means of elementary form, not forming a specific part of the present invention per se, is shown in Figure 11, and in-

cludes a worm gear 35 fixed to the turntable 31 and a worm 36 meshing with gear 35 and driven by a motor 37.

It is thought that the operation of the vessel will be readily apparent from a consideration of the foregoing. Briefly, the Diesel engines 25 and the propellers 24 are utilized to drive the vessel in harbors and other restricted areas where low speed and considerable maneuvering are desired. However, when the ship is underway at sea the airplane 32 constitutes the propulsion means. The airplane 32 pulls the hull 1 forwardly and raises the bow thereof from the water, causing said hull to plane on the hydrofoil 26. The construction and arrangement of the hydrofoil 26 beneath the aft portion of the hull 1 is such that great stability as well as high speed is had. When the airplane 32 is not in use, as when the vessel is moving in a harbor, said airplane is turned in a horizontal plane in a circle of 90 degrees through the medium of the turntable 31 for paralleling the wing of said airplane to the hull 1. The airplane may be turned and operated at the same time for assisting in maneuvering the vessel. The turntable 31 may be operated in any suitable manner. The partition 11 constitutes a girder for strengthening the hull 1 longitudinally against sagging or buckling when the bow is raised by the airplane 32.

It is believed that the many advantages of a ship constructed in accordance with the present invention will be readily understood, and although a preferred embodiment is as illustrated and described, it is to be understood that changes in the details of construction and in the combination and arrangement of parts may be resorted

to which will fall within the scope of the invention as claimed.

What is claimed is:

1. A ship comprising, in combination, a ship hull having rear marine propulsion and steering means, a hydrofoil mounted on the bottom of the aft portion of the hull and having a forwardly inclined bottom surface located below the bottom of the hull, and an airplane having a fuselage secured and mounted on top of the forward portion of the hull for propelling the ship and lifting the forward end of the hull, said hull extending a considerable distance rearwardly of the airplane and having a maximum width substantially approximating the wing span of the airplane, a horizontal turntable rotatably mounted on a vertical axis upon the forward portion of the hull, said airplane being fixed on said turntable for rotation therewith relative to the hull to aid in maneuvering the latter.
2. A ship comprising, in combination, a ship hull having rear marine propulsion and steering means, and an airplane having a fuselage secured and mounted on top of the forward portion of the hull for propelling the ship and lifting the forward end of the hull, said hull extending a considerable distance rearwardly of the airplane and having a maximum width substantially approximating the wing span of the airplane, and a horizontal turntable rotatably mounted on a vertical axis upon the forward portion of the hull, said airplane being fixed on said turntable for rotation therewith relative to the hull to aid in maneuvering the latter.

35 JAMES E. SYKES.
